MUFFLER INCLUDING TAPERED INLET
NOZZLE WITH TAPERED OPENINGRaymond C. Baird, Los Angeles, Calif., assignor
to The Fluor Corporation, Ltd., Los Angeles,
Calif., a corporation of California

Application May 19, 1947, Serial No. 748,961

7 Claims. (Cl. 181—33)

1

This invention has to do generally with the elimination of sound, vibratory and other effects caused by the flow or undulating characteristics of gas streams; the invention having particular applicability for the elimination of such effects in equipment such as mufflers or dampers intended to suppress either or both audible and sub-audible undulation frequencies in the gas.

The invention is aimed primarily at the elimination of vibrations and sounds created or existing at the point of discharge of the gas from a conduit, as from the inlet pipe of a muffler or damper. Considering engine mufflers as typical, there exists a tendency for resonance to be created in the exhaust pipe itself by reason of abrupt discontinuity in the cross-sectional area of the pipe at the point of gas discharge into the muffler chamber or shell. In its major aspects the invention has for its object to reduce the magnitude of reflected acoustical energy at the muffler inlet to a degree, eliminating the disturbances normally created by such energy, and in so doing, to materially improve the over-all efficiency of the muffler as a whole.

Briefly, the invention is in the nature of an acoustic discontinuity diffuser comprising an appropriate body structure forming a gas passage of gradually decreasing cross-sectional area from which the gas is released through one or more openings extending longitudinally of the passage and having progressively increasing size or width. Acoustically speaking, an injector of this type affords to the gas flowing through a passage having the stated characteristics, a progressively decreasing impedance which may approach zero toward the end of the passage. Exhaust gases may leave the passage from any location along its length in a quantity which is small as compared with the gas remaining and advancing in the passage beyond such location. Thus the ratio of the gas escape to the continued flow in the passage may increase from zero at the entrance of the injector, to a maximum at its end. A result of major significance is that the energy reflected by the cross-sectional area variances of the injector is so small relative to that of the incident gas stream, that there is little tendency for the creation of pipe resonance. In addition, the incremental energy reflections produced along the gas escape openings are shifted in phase relative to the direction of gas flow, to further discourage resonance. At this point it may be mentioned that when contained in for example a muffler chamber, the described characteristics of

2

the injector tend also to inhibit chamber resonance.

In suppressing shock resonance of the muffler because of the explosive pulses contained in the exhaust gas, the injector acts as a filter whereby the energy at any point along the pulse wave is distributed lengthwise of the injector so that path differences in the muffler chamber result in phase shift. The consequent filtering or pulse smoothing effect suppresses shock waves of such magnitude as to cause mechanical vibration of the muffler shell. Advantage is taken of this further filtering effect in that alteration of the incident wave characteristics facilitates the ultimate sound muffling to be accomplished.

Further details of the contemplated injector, as well as its association with an exhaust gas muffler, will be understood from the following detailed description of certain illustrative embodiments of the invention, reference being had throughout the description in the accompanying drawing, in which:

Fig. 1 is a view showing the muffler in vertical section;

Fig. 2 is a cross-section on line 2—2 of Fig. 1; Figs. 3 and 4 are sectional views illustrating variational forms of the invention; and

Fig. 5 is an enlarged cross-section on line 5—5 of Fig. 3.

While specifically adaptable to mufflers having any desired gas inlet and outlet arrangement, I have selected as illustrative a vertical type muffler having a shell 10 provided with a lower side inlet 11 and a top outlet 12. The shell 10 contains a transverse partition 13 dividing the shell interior into an inlet chamber 14 and a communicating chamber 15 within which undulations remaining in the gas stream flowing from chamber 14, are eliminated or damped by appropriate sound absorbing means, of which the later described muffler structure is to be regarded as typical.

Chamber 14 contains the acoustical diffuser, generally indicated at 16, which may have any of various forms possessing the characteristic of presenting to the entering gas stream an elongated passage of progressively decreasing cross-sectional area, from which the gas is released into the chamber through one or more slot-like openings of progressively increasing width or size. As illustrative, the diffuser may comprise a hollow, channel shaped shell 17 connected by adaptor 18 with the gas inlet line 19. As illustrated in Fig. 2, the shell extends circularly within the chamber and forms with the muffler shell 10 a passage

20 which progressively diminishes from a maximum cross-sectional area at its inlet end 21, to a minimum cross-sectional area at the passage terminal 22. The channel flanges 23 are spaced at 24 from the shell 10 to form openings whose width progressively increases as the passage area decreases, and through which the gas is progressively released into the chamber 14 along the course of its flow within the channel passage. As a result the gas is prevented by its diffused release from creating impulses which might otherwise result from discharge through an ordinary open end conduit.

Fig. 3 illustrates a variational form of diffuser 25 comprising a hollow shell 26 receiving gas from the inlet or adapter 27 and having a pair of symmetrical branches 26a whose cross-sectional areas progressively reduce toward the ends of the branches welded to the shell 10 at 28. The edges of the diffuser sides or flanges 29 are spaced from a V-shaped baffle 30 to form the gas discharge openings 31, the width of which progressively increases toward the branch extremities, as illustrated.

Fig. 4 shows a further variational form of diffuser adapted to be positioned vertically within a muffler shell S having a lower side gas inlet 34. Here the diffuser may comprise a circular or square cross-section hollow shell 32 connected by adapter 33 with the inlet 34, and having a pair of gas escape branches 35 and 36 tapering outwardly to define passages of progressively decreasing cross-sectional area. As illustrated, the branches 35 and 36 may have different lengths. The gas escapes from the branch passages through progressively widening slots or openings 37 formed by splitting the branch shells longitudinally.

Referring to Fig. 1, chamber 15 contains a plurality of perforated tubes 38, 39 and 40 spaced concentrically within the shell 10 to define between the tubes annular passages 41 and 42 through which the gas flows in the courses indicated by the arrows. Tubes 39 and 40 have a top closure 43 which requires the gas flowing from chamber 14 through tube 38 to reverse its flow in passing downwardly through space 41, and again into space 42 from which the gas is released through the perforations 44 into chamber 15, the gas thence of course flowing through the outlet 12. Simultaneously with its flow longitudinally through passages 41 and 42, the gas is released transversely thereto through the perforations in the tubes 38 and 39, all to the end that the resulting divisions and co-mingling of the gas along its course of flow produces muffling effects to a high degree. Structural and functional details of this type of concentric perforated tube muffler, are more particularly dealt with in Patent No. 2,363,236 issued November 21, 1944, to P. E. Fluor on "Air-Cooled Muffler."

I claim:

1. A gas undulation damper including a shell containing a chamber having an inlet, and an acoustical discontinuity diffuser within said chamber comprising a body communicating with said inlet and containing an elongated tapered passage of progressively decreasing cross-sectional area in the direction of the gas flow therethrough and from which the gas escapes through a discharge opening of progressively increasing size coextensive with said tapered passage and defined by straight edges of said body intersecting at a point.

2. A gas undulation damper including a shell containing a chamber having an inlet, and an

acoustical discontinuity diffuser within said chamber comprising a body communicating with said inlet and containing an elongated tapered passage of progressively decreasing cross-sectional area in the direction of the gas flow therethrough and from which the gas escapes through a slot-like gas discharge opening of gradually and progressively increasing width in the direction of gas flow through said passage said body being

10 open for straight line flow of the gases at the discharge end of said passage and said discharge opening being coextensive with said tapered passage and defined by straight edges of said body intersecting at a point.

15 3. A gas undulation damper including a shell containing a chamber having an inlet, and an acoustical discontinuity diffuser within said chamber comprising a body communicating with said inlet and containing an elongated tapered 20 passage of progressively decreasing cross-sectional area in the direction of the gas flow therethrough and from which the gas escapes through a plurality of slot-like discharge openings at opposite sides of said passage and having progressively increasing width in the direction of gas flow through the passage, said discharge openings being coextensive with said tapered passage and defined by straight edges of said body intersecting at a point.

30 4. A gas undulation damper including a shell containing a chamber having an inlet, and an acoustical discontinuity diffuser within said chamber comprising a body communicating with said inlet and containing an elongated tapered 35 passage of progressively decreasing cross-sectional area in the direction of the gas flow therethrough, said body being spaced from said shell to form therewith a slot-like gas discharge opening of gradually and progressively increasing width in the direction of gas flow through said passage, said opening being coextensive with said tapered passage and being defined by straight edges intersecting at a point.

45 5. A gas undulation damper including a cylindrical shell containing a chamber having an inlet, and an acoustical discontinuity diffuser within said chamber comprising a circularly curved body communicating with said inlet and containing an elongated tapered passage of progressively decreasing cross-sectional area in the direction of the gas flow therethrough, said body being spaced from said shell to form with its cylindrical wall a slot-like gas discharge opening of gradually and progressively increasing width in the direction of gas flow through said passage, said opening being coextensive with said tapered passage and being defined by straight edges intersecting at a point.

50 6. A gas undulation damper including a shell containing a chamber having an inlet, and an acoustical discontinuity diffuser within said chamber comprising a hollow body shell communicating with said inlet and tapered therefrom to contain an elongated tapered passage of 65 progressively decreasing cross-sectional area in the direction of the gas flow therethrough and from which the gas escapes through a narrow slot in the tapered portion of the shell, the discharge end of said shell being open and said slot having progressively increasing width in the direction of gas flow through the passage coextensive with said tapered passage and being defined by straight edges of said shell intersection at a point.

70 7. A gas undulation damper including a shell

containing a chamber having an inlet, and an acoustical discontinuity diffuser within said chamber comprising a hollow body shell communicating with said inlet and having a plurality of branches tapered longitudinally to contain elongated tapered passages each of progressively decreasing cross-sectional area in the direction of the gas flow therethrough and from which the gas escapes through a gas discharge slot in each branch of gradually and progressively increasing width in the direction of gas flow through the passage.
